(57) **CLAIM**

The ornamental design for a case for portable electronic computing device including keyboard, as shown and described.

DESCRIPTION

FIG. 1 is a front perspective view of a first embodiment.

FIG. 2 is a rear perspective view of a first embodiment.

FIG. 3 is a front elevational view thereof.

FIG. 4 is a rear elevational view thereof.

FIG. 5 is a top elevational view thereof.

FIG. 6 is a bottom elevational view thereof.

FIG. 7 is a right elevational view thereof; and,

FIG. 8 is a left elevational view thereof.

The features shown in broken lines in the drawing figures depict features that form no part of the claimed design.
